REFLECTOR BUTTON SIGN

Marion C. Almes, Cuyahoga Falls, Ohio

Application September 7, 1944, Serial No. 552,958

2 Claims. (Cl. 40—130)

1

The present invention relates to signs and more particularly to a novel sign construction in which the reflector members or surfaces cannot be readily removed.

Among the objects of the present construction is the provision of a novel anchor plate for the reflector members, units or surfaces whereby they are held safe from pilfer.

A further object of the invention is the provision of a novel letter, numeral, design or other suitable insignia constructed of a substantially indestructible material having a longer life and able to withstand greater natural wear, shocks and abuse than such parts of signs now in use.

Another object of the present invention is the provision of a novel sign construction in which the reflecting units or surfaces are rigidly and non-removably held in position by an anchor plate embedded in the plastic material of the letters, numerals, designs or insignia of the sign. In the preferred embodiment, such plastic material consists of rubber, rubber composition or other suitable composition capable of being molded as for example the commercial composition known as tenite.

Still another object of the present invention is to provide a molded letter, numeral, design or other insignia with reflector members or surfaces, permanently held in an anchor plate molded in the letter, numeral, design or other insignia and rivet holes passing through the letter, numeral, design or other insignia whereby said letter, numeral, design or other insignia may be riveted to a mounting.

Heretofore in signs of the reflector type that employed reflector members such as glass buttons have suffered very frequent damage from unauthorized persons removing the reflector members often by the simple expedient of a pocket knife by which they lift or gouge the reflector member from its socket or seat. The extent of this pilfering has grown until it presents a serious problem and expense to those who maintain reflector type signs. By reason of the present construction the reflector members or units cannot be removed without cutting through a bolt which requires entirely too much effort to be practiced for the reward of obtaining a few reflector members.

The invention resides in the combination, construction, and arrangements of parts illustrated in the accompanying drawing, and while there are shown therein two embodiments, it is to be understood that the same is susceptible of modification and change and comprehends other de-

2

tails, arrangements of parts, features and constructions, without departing from the spirit of the invention.

In the drawing:

5 Fig. 1 is a perspective view of a sign involving this invention.

Fig. 2 is a plan view of an anchor plate used in a letter "S" showing rivet holes and holes through which reflector members will protrude.

10 Fig. 3 is a side elevation of a reflector member.

Fig. 4 shows a reflector member in position the view being taken on line 4—4 of Fig. 2.

Fig. 5 is a plan view of a letter "S" punched from a sheet of rubber.

15 Fig. 6 is a plan view of a letter "S" punched from a sheet of rubber and showing holes through which reflector members will protrude.

Fig. 7 is the assembly of the parts shown in Figs. 2, 3, 5 and 6 and shows the assembly as it

20 will appear before being pressed together by a vulcanizing mold.

Fig. 8 is a cross-sectional view taken on line 8—8 of Fig. 1.

Referring to the drawing it will be seen that in 25 one form the invention consists of a mounting plate 10 which may be composed of metal, wood or of any other suitable material sufficiently firm and rigid to retain a rivet or bolt. Attached to the mounting plate 10 are letters 11, 12, 13 and 30 14. These letters are molded rubber letters and in the disclosed embodiment the letter "S" or part is described by way of illustrating the invention. In Fig. 2 is shown the anchor plate 15 which may be of sixteen gauge sheet iron or of 35 any other suitable rigid material or material that will become rigid as, for example, unvulcanized hard rubber compound that will become hard during the vulcanization and molding process of the letter 11 which will be presently mentioned.

40 The anchor plate 15 has punched therein holes 16 which are spaced apart and positioned so as to properly locate reflector members to outline the letter "S." In each of the holes 16 in the anchor plate 15 is placed a reflecting member 17. This reflector member is of glass having shoulders 18 and 19. The members 17 are projected into the holes 16 so that the reflector surfaces face one way.

A rubber backing 20 shown in Fig. 5 is punched 45 from a sheet of unvulcanized rubber compound of approximately .250" thick. For this backing blank I prefer a soft rubber compound of about the consistency of a pneumatic automobile tire tread stock. This strip or blank 20 is placed over 55 the back of the reflector members 16 as they are

in position in their anchor plate 15. As will be seen by referring to Fig. 7 the edges of the backing strip 20 extend beyond the edges of the anchor plate 15.

A facing strip or blank 21 shown in Fig. 6 is punched out of a strip of unvulcanized rubber of approximately .125" thick. It is preferred that the rubber compound in this strip 21 to be the same as that described for backing strip 20. Strip 21 has formed in it holes 22 which are so spaced and arranged as to fit over that part of the reflector members 17 which extend through the anchor plate 15. By referring to Fig. 7 it will be seen that the edges of facing strip 21 extend beyond the edges of the anchor plate 15 and that the backing strip 20 and the facing strip 21 are approximately the same width and that the anchor plate 15 is sandwiched between them.

By reference to Figures 6 and 7 it will be seen that the holes 16 in the anchor plate 15 are not large enough to permit the anchor plate to pass over the shoulder 18 of the reflector member 17.

Referring again to Fig. 2 rivet holes 23 extend through the anchor plate.

The molding of the letter 11 or "S" is done in the usual manner of molding rubber goods and a detailed description of the vulcanizing mold and method of vulcanizing is considered unnecessary. The lid or top of the mold has formed in it recesses to receive the reflector face of the reflector member 17 and these faces act as aligning means to locate the anchor plate in the mold cavity. The lid of the mold carries pins which pierce through the facing strip 21 passing through the holes 23 in the anchor plate and through the backing strip 20 to form rivet holes 24. After molding and vulcanization the letter 11 or "S" is removed from the mold when it will be found to present a neat attractive appearance the parts 21 and 20 being vulcanized firmly together entirely surrounding and covering the anchor plate 15. The reflector surfaces of the reflector members 17 extend above the face of the letter "S" thus exposing the member 17 to the light of reflecting purposes.

The member 11 is attached to the mounting plate 10 by means of rivets 25.

In similar manner the members 12, 13 and 14 are made and used.

It will now be seen that the reflector units 17 cannot be lifted from their position in the sign as the letter, numeral, design or other insignia is riveted to the mounting plate and the rivet passes through the rigid anchor plate 15 which in turn anchors the reflector member 11 securely in position the reflector members shoulder 18 being too large to pass through the hole 16 in the anchor plate and the mounting plate 10

blocking access to the reflector members through the rubber backing 20.

It will be obvious to those familiar with the art that applicant's invention may be modified by forming strip 21 without the holes 22 and then assemble the members 20, 21 and 22 as shown in Fig. 7 but without the reflector 17. In this modification the mold on either the top or bottom will carry pins having shoulders corresponding to the shoulders 18 and 19 of the reflector 17 which pins will form a reflector receiving hole through the symbol. The sign will then be assembled by placing the reflectors in position in the holes so formed in the symbol and the symbol bolted or otherwise fastened to its mounting plate with the back of the symbol resting against the mounting plate and the reflector end of the symbol projecting through the face of the symbol.

I claim:

1. A sign comprising a rigid mounting plate, at least one symbol permanently attached to said mounting plate, said symbol consisting of a rigid anchor plate having holes spaced apart therein at predetermined positions, said holes defining the shape of the symbol, a reflector member positioned in each of said holes through said symbol, said reflectors having shoulders too large to pass through said anchor plate, a rubber backing and facing molded and vulcanized about said anchor plate with holes formed through said facing at each hole in the anchor plate, said symbol being attached to the mounting plate with said shoulders of the reflectors mounted therein in contact with said rigid anchor plate and with the end of the reflectors protruding beyond the surface of the said rubber facing.

2. A sign comprising a mounting plate, a rigid anchor plate having the general outline of a symbol to be displayed, a facing and backing about the anchor plate, said anchor plate and facing having aligned holes therethrough adapted to receive reflector members therein, said holes defining the shape of said symbol, reflector members having shoulders too large to pass through said holes in the anchor plate, said reflector members projecting through said holes in said anchor plate, the anchor plate having at least one attachment hole therethrough adapted to receive a bolt-like attachment member, said anchor plate with its facing and backing, reflector member and mounting plate being permanently fastened together by attachment means extending through said attachment hole and mounting plate with exposed ends of said reflector members extending beyond the surface of said facing.

MARION C. ALMES.
